(57) **CLAIM**

The ornamental design for a portable phone, as shown and described.

DESCRIPTION

- FIG. 1 is a perspective view of a portable phone;
FIG. 2 is a front view of the portable phone of FIG. 1;
FIG. 3 is a rear view of the portable phone of FIG. 1;
FIG. 4 is a left-side view of the portable phone of FIG. 1;
FIG. 5 is a right-side view of the portable phone of FIG. 1;
FIG. 6 is a top plan view of the portable phone of FIG. 1;
FIG. 7 is a bottom plan view of the portable phone of FIG. 1;
and

FIG. 8 is a front view of the portable phone of FIG. 1, displaying speakers, when upper and lower portions on a rear part of the phone are slid upward and downward, respectively; and,

FIG. 9 is a rear view of the portable phone of FIG. 8.

The broken lines and the surfaces within the upper and lower open rectangular spaces in the FIG. 9 view represent the

bounds of the claimed design while all other broken lines are directed to environment and are for illustrative purposes only; the broken lines form no part of the claimed design.
